UNITED STATES PATENT OFFICE.

FRANK C. ANDERSON, OF CINCINNATI, OHIO.

INTERLOCKING SWITCH-STAND MECHANISM.

1,106,533.

Specification of Letters Patent. Patented Aug. 11, 1914.

Application filed October 15, 1913. Serial No. 795,222.

To all whom it may concern:

Be it known that I, FRANK C. ANDERSON, a citizen of the United States, residing at Cincinnati, in the county of Hamilton and State of Ohio, have invented certain new and useful Improvements in Interlocking Switch-Stand Mechanisms, of which the following is a specification.

My invention relates to means for insuring safety in the use of railway switches, the object being to render it impossible to lock a switch until the point-rail has been brought against the stock-rail.

My invention consists in the parts and in the details of construction and arrangement of parts as will hereinafter be more fully described and claimed.

In the drawings: Figure 1 is a general perspective view of part of a switch and a switch stand embodying my invention; Fig. 2 is a detail of the switch-operating lever and the disengageable interlock-operating lever; Fig. 3 is a detail perspective view of the bell crank that operates the interlocking plunger; Fig. 4 is a plan view of the interlocking mechanism; Fig. 5 is a vertical-longitudinal section on the line $\alpha-\alpha$ of Fig. 4; and Fig. 6 is a similar section, but showing a modification.

20 In the construction herein shown as an example, the switch stand 1 has the top plate 2 and the vertical main shaft 3, which is connected by means of the crank 4 and rods 5 and 6 to the point-rail 7 of the switch.

35 The shaft 3 has the fulcrum-head 8 fixed to it and the switch-operating lever 9 swings in a vertical plane on a pivot 10 in its fulcrum-head. When the lever 9 is down in vertical position, it will engage either in the

40 slot 11 or the slot 12 in the plate 2, accordingly as the switch is closed or opened. Stop lugs 13 and 14 are provided adjacent to the slots 11 and 12, respectively, to limit the swinging of the fulcrum-head 8 in its

45 horizontal plane, which swinging is permitted when the switch-operating lever 9 is raised out of the slot 11 or slot 12 to horizontal position. Above this pivot 10, the lever 9 has the ear 15, with an opening 16

50 to receive the shackle of a padlock; and the fulcrum-head 8 and this lever are so shaped in the region of this ear 15 that the shackle of the padlock in the opening 16 will engage with the outside of the fulcrum-head and

55 prevent the lever 9 from being raised out of either the slot 11 or the slot 12. Thus the

switch may be locked in closed or open position.

The switch stand 1 is mounted on the head blocks 17, and one of these, close to the switch stand, between the switch stand and the track, is gained or recessed and receives a housing 18. The point-rail 7 of the switch has a guard 19 bolted to it, as seen in Fig. 1, and the interlocking-bar 20 is secured to this guard 19 by means of nuts 21, flanking the guard and adjustable along a rounded part 22 of the bar 20. This bar 20 slides through a part of the housing 18 that extends outside the head block 17. A 60 guide 23 for the interlocking-bar 21 is also provided on the head block 17 about midway between the housing 18 and the track to reinforce said bar and render the operation of the apparatus more accurate. The 65 housing 18 is bolted to the under side of a plate 24 which lies flat on the upper side of the head block 17, completely covering the recess or gain in the head block and being screwed or otherwise suitably secured to the 70 head block, as shown in Fig. 1. Sliding horizontally in the housing 18, at right angles to the interlocking-bar 20, is the interlocking-plunger 25. The interlocking-bar 20 has an opening 26, and this interlocking-plunger 25 can extend through this opening 75 and out through the outside of the housing 18 when the point-rail 7 is drawn up close to the stock-rail of the track and is perfectly 80 safe for traffic. The parts are so made however, that if the point-rail 7 is, for any 85 reason, left any appreciable distance away from the stock rail, the plunger 25 cannot 90 enter the opening 26.

It is the purpose of my invention to 95 provide simple and effective mechanism that will so connect the switch-operating mechanism and this interlocking-mechanism that the switch cannot be locked unless this plunger 25 has entered this opening 26 in the 100 interlocking-bar 20, and this will now be described.

Secured to the upper side of the plate 24 is a crank-casing 27 with a cover 28 secured to its top and holding, in bearings formed in said casing and cover, the transverse shaft 29, which makes up, with the arm 30 and the arms 31, a bell-crank of integral construction. The plunger 25, as shown in Fig. 5, has a head 32 fixed on it, inside the housing 18, and the arm 30 of the bell-crank extends down and engages in this head 32 in 110

such a manner that if the arms 31 of the bell-crank are raised, this arm 30 will pull the plunger 25 back from the interlocking-bar 20.

5 On the switch stand is the disengageable interlock-operating lever 33, which has a pivot 34 in the stop 13, this pivot being concentric with the pivot 10 of the switch-operating lever 9 when the fulcrum-head 8 is up against the stop 13 in such position as to permit the lever 9 to drop into the slot 11. This lever 33 has a lateral boss 35 extending over toward the switch-operating lever 9 and carrying a lug 36 that enters 15 a recess 37 in the switch-operating lever 9 when said lever 9 is brought up toward the lever 33.

About in alignment with the boss 37 and the lug 36, is a stud or pivot 38, on the lever 20 33, by means of which the connecting-rod 39 is connected to said lever 33. This connecting-rod 39 extends down and has a rounded part 40 that is screwed into a T-head 41 and provided with a lock nut 42 25 to fix it therein. This T-head 41 is brought between the arms 31 of the bell-crank and a pivot pin 43 passes through the arms and through the horizontal part of the T-head. With the parts thus arranged, when it is 30 desired to open the switch, finding the lever 9 and the other parts in the positions shown in Fig. 1, the operator removes the padlock from the ear 15 and raises the lever 9 to its horizontal position so as to release it 35 from the slot 11. In doing this he raises the interlock-operating lever 33 along with the lever 9, due to the engagement of the lug 36 in the recess 37 in said lever 9. Raising this lever 33 thus to its horizontal position, it operates, through the connection by 40 means of the rod 39 and the T-head 41, to raise the arms 31 of the bell-crank, which, as before described, withdraws the plunger 25 from the interlocking-bar 20. When this 45 plunger is thus withdrawn, the switch may be opened by swinging the lever 9 with its fulcrum-head 8 around in the horizontal plane. In thus swinging these parts around, the lever 9 leaves the interlock-operating 50 lever 33 with its lug 36 withdrawn from the recess of said lever 9. This lever 33 will thus remain in raised horizontal position with the interlocking-plunger 25 withdrawn from the interlocking-bar 20, because, in 55 opening the switch, the interlocking-bar 20 has been pulled out, due to its connection with the point-rail 7 by means of the guard 19, until the opening 26 in said interlocking-bar is drawn away from the end of the plunger 25.

When the switch is to be closed, the lever 9 and the fulcrum-head 8 are swung back in the horizontal plane, and, as they approach the closed position, the recess 37 in 65 the lever 9 will again receive the lug 36 of

the interlock-operating lever 33. Now, if the operator is to move said lever 9 down to its vertical position within the slot 11, it is necessary to force the interlock-operating lever 33 down, and, for this lever to go down, 70 it is necessary for the plunger 25 to enter the opening 26 in the interlocking-bar 20. As above described, the parts are so arranged that this opening 26 will not be in position to admit the plunger 25 as 75 long as the point-rail 7 is any appreciable distance away from the stock-rail of the track. Therefore it will be seen that it will be impossible for the operator to bring the switch-operating lever 9 down 80 to vertical position with its ear 15 protruding to receive the padlock unless the point-rail 7 has actually been brought up to safe position and the plunger 25 has entered the opening 26 in the interlocking-bar 20. Therefore it will be impossible for 85 a careless operator to lock the switch in unsafe position whether this be due to wear and looseness in the connections between the switch-stand and the rails or whether it be 90 due to some obstruction between the point-rail and the stock-rail, which, even though it were slight, might hold the point-rail 7 far enough away for a sharp flange to enter 95 between the point-rail and the stock-rail and result in derailment. Where the obstruction is small it is especially dangerous, because without an interlocking-mechanism the operator may strain the parts of the switch-stand and switch sufficiently to accomplish the locking of the switch-stand with the obstruction in place. The interlocking-mechanism prevents this; and my improved connections enable this mechanism 100 to be operated with a minimum of parts to 105 the mechanism and of wear and of attention required on the part of the operator.

By making the bell-crank as shown, with the two arms 31 lying outside the casing 27 and its cover 28, and with the arm 30 inside thereof, the opening in the casing is confined to the journal bearing around the shaft 29 of the bell-crank, which can be made sufficiently tight to prevent entrance of moisture or other foreign matter. This is an 110 important consideration, the housing 18 being also constructed with this in view. I also reduce the expense of construction and maintenance considerably by making the two arms 31, the arm 30 and the shaft 29 115 integral. The parts of the shaft 29 that lie in the bearings may be turned and the ends of the arms 31 may be bored in alignment 120 to pivot with the T-head 41 with far less work than would be necessary to assemble 125 the different parts made separately. One of the arms 31 is provided with a projection 44 with which the square head of the pin 43 engages so that the pin is prevented from 130 turning in the arms and all of the wear

takes place between the pin and the T-head 41.

By providing the rod 39 with the reduced threaded part 40 screwed into the T-head 5 41, the length of this connection may be adjusted so that the bringing of the interlock-operating lever 33 to horizontal position will withdraw the plunger 25 just the proper 10 distance to clear the interlocking-bar 20 and thereby insure that these parts will remain in their raised positions when the lever 9 is drawn away from the lever 33 ready to re-engage upon the return of the lever 9.

The device shown in Fig. 6 is like that 15 shown in the other figures excepting that the plunger 25 is provided with a rack 45 and the bell-crank has a segment gear 46 substituted for the arm 30. This segment gear, meshing with the rack 45, withdraws the 20 plunger 25 from the interlocking-bar 20 when the arms 31 of the bell-crank are raised in the manner hereinbefore described.

To guard against withdrawal of the plunger 25 from the interlocking-bar 20, should 25 the switch stand and other exposed mechanism be dislocated or destroyed, the plate 24 is provided. This plate will permit the casing 27 and other parts supported thereby to be destroyed and will yet cover and hold 30 down the housing 18 and the plunger 25 therein. Where it is desired to provide additional insurance against withdrawal of the plunger in case of such an accident, a suitable locking device may be provided to 35 engage with the plunger 25 and be released manually before the operator attempts to raise the lever 9 and the interlock-operating lever 33 therewith, such locking devices being of various descriptions and the manner 40 of their application to the interlocking-mechanism not being novel, no specific description thereof is deemed necessary herein. It will also be understood that various other modifications of my invention are possible 45 without departing from the scope or spirit thereof, which is defined by the following claims.

I claim—

1. In switch-interlocking mechanism, an 50 interlocking-bar connected to the point-rail of a switch, a plunger adapted to engage across said bar, throwing means for said plunger, a switch-operating lever requiring initial movement in one plane before it can 55 be moved in another plane to throw the switch, an interlock-operating lever movable with the switch-operating lever during the initial movement thereof, but disengageable therefrom when the switch-operating lever 60 is moved to throw the switch, and operative connection between the interlock-operating lever and said throwing means for the plunger.

2. In switch-interlocking mechanism, an 65 interlocking-bar connected to the point-rail

of the switch, a plunger adapted to engage across said bar, a bell-crank adapted to throw said plunger, a switch-operating lever requiring initial movement in one plane before it can be moved in another plane to 70 throw the switch, an interlock-operating lever movable with the switch-operating lever during initial movement thereof, but disengageable therefrom when the switch-operating lever is moved to throw the switch, 75 and a connecting element from said interlock-operating lever to said bell-crank.

3. In switch-interlocking mechanism, an interlocking-bar connected to the point-rail 80 of a switch, a plunger adapted to engage across said bar, throwing means for said plunger, a switch-operating lever requiring initial movement in one plane before it can be moved in another plane to throw the switch, an interlock-operating lever movable 85 with the switch-operating lever during the initial movement thereof, but disengageable therefrom when the switch-operating lever is moved to throw the switch, operative connection between the interlock-operating 90 lever and said throwing means for the plunger, and means for adjusting said operative connection.

4. In switch-interlocking mechanism, an interlocking-bar connected to the point-rail 95 of the switch, a plunger adapted to engage across said bar, a bell-crank adapted to throw said plunger, a switch-operating lever requiring initial movement in one plane before it can be moved in another plane to 100 throw the switch, an interlock-operating lever movable with the switch-operating lever during initial movement thereof, but disengageable therefrom when the switch-operating lever is moved to throw the 105 switch, a connecting element from said interlock-operating lever to said bell-crank, and means for adjusting the length of said connecting element.

5. In switch-interlocking mechanism, an 110 interlocking-bar connected to the point-rail of the switch, a plunger engaging across said bar, throwing means for said plunger, a switch-operating lever requiring initial movement in one plane before it can be 115 moved in another plane to throw the switch, an interlock-operating lever movable in a plane substantially parallel with the plane of initial movement of the switch-operating lever, a lug carried by the interlock-operating lever, said switch-operating lever having a recess receiving the lug, said lug being adapted to be disengaged from the recess when the switch-operating lever is moved to 120 throw the switch, and operative connection 125 between said interlock-operating lever and the throwing means for the plunger.

6. In switch-interlocking mechanism, in combination with a switch-stand and a main shaft thereon and connection between said 130

main shaft and the point-rail of the switch, a fulcrum-head fixed to the main shaft, a switch-operating lever having a pivot in said fulcrum-head, a plate having a slot 5 within which the switch-operating lever engages, said lever being initially swung out of said slot in one plane, for movement with the fulcrum-head in another plane, to rotate the main shaft and throw the switch, an interlock-operating lever having a pivot concentric with the pivot of the switch-operating lever during the initial movement thereof, means for engagement between the interlock-operating lever and the switch-operating lever whereby they swing together during said initial movement, but whereby they disengage during the movement of the switch-operating lever to throw the switch, an interlocking-bar connected to the point-rail of the switch, an interlocking-plunger adapted to engage across said interlocking-bar, throwing means for said plunger, and operative connection between said interlock-operating lever and said throwing means for the plunger.

7. In switch-interlocking mechanism, in combination with a switch-stand and a main shaft thereon and connection between said main shaft and the point-rail of the switch, a fulcrum-head fixed to the main shaft, a switch-operating lever having a pivot in said fulcrum-head, a plate having a slot within which the switch-operating lever engages, said lever being initially swung out of said slot in one plane, for movement with the fulcrum-head in another plane, to rotate the main shaft and throw the switch, an interlock-operating lever having a pivot concentric with the pivot of the switch-operating lever during the initial movement thereof, means for engagement between the interlock-operating lever and the switch-operating lever whereby they swing together during said initial movement, but whereby they disengage during the movement of the switch-operating lever to throw the switch, an interlocking-bar connected to the point-rail of the

switch, an interlocking-plunger adapted to engage across said interlocking-bar, throwing means for said plunger, operative connection between said interlock-operating lever and said throwing means for the plunger, said switch-operating lever having means for locking it in position after it has fully entered the slot in the plate, but said means being unavailable until said plunger has engaged across said interlocking-bar.

8. In switch-interlocking mechanism, plunger-throwing means comprising, integrally formed, a transverse shaft, an engaging member extending from near the middle of said shaft in one direction, and arms near the ends of said shaft extending substantially parallel to each other in another direction.

9. In switch-interlocking mechanism, in combination with a casing and a cover therefor, plunger-throwing means comprising, rigidly secured to each other, a transverse shaft journaled between said casing and said cover, an engaging member extending from near the middle of said shaft within said casing, and arms extending from the ends of said shaft outside the casing substantially parallel to each other in another direction.

10. In switch-interlocking mechanism, in combination with a casing and a cover therefor, plunger-throwing means comprising, rigidly secured to each other, a transverse shaft journaled between said casing and said cover, an engaging member extending from near the middle of said shaft within said casing, arms extending from the ends of said shaft outside the casing substantially parallel to each other in another direction, a T-head between the end parts of said parallel arms, a pivot pin passing through the transverse part of the T-head and through said arms, and a connecting rod adjustably secured in the stem member of said T-head.
